(57) CLAIM

The ornamental design of the combined wheelchair arm rest and compartment, as shown and described.

DESCRIPTION

FIG. 1 is a perspective view of the combined wheelchair arm rest and compartment of my new design;

FIG. 2 is a top plan view thereof;

FIG. 3 is a front elevational view thereof;

FIG. 4 is a rear elevational view thereof;

FIG. 5 is a side elevational view of the left side thereof;

FIG. 6 is a side elevational view of the right side thereof;

FIG. 7 is a bottom plan view thereof;

FIG. 8 is a perspective view of the combined wheelchair arm rest and compartment of FIG. 1 showing the arm rest in the open position;

FIG. 9 is a top plan view of FIG. 8;

FIG. 10 is a front elevational view of FIG. 8;

FIG. 11 is a rear elevational view of FIG. 8;

FIG. 12 is a side elevational view of the left side of FIG. 8;

FIG. 13 is a side elevational view of the right side of FIG. 8, and;

FIG. 14 is a bottom plan view of FIG. 8.
